US00D768134S

(12) **United States Design Patent** (10) **Patent No.:** **US D768,134 S**
(45) **Date of Patent:** **** Oct. 4, 2016**

(54) **ELECTRONIC DEVICE**

(71) Applicant: **Apple Inc.**, Cupertino, CA (US)

(72) Inventors: **Bartley K. Andre**, Palo Alto, CA (US);
John M. Brock, San Francisco, CA (US);
Matthew Phillip Casebolt, Fremont, CA (US); **Brett William Degner**, Menlo Park, CA (US); **Ron Alan Hopkinson**, Campbell, CA (US); **Eugene Kim**, San Francisco, CA (US); **Chris Ligtenberg**, San Carlos, CA (US); **John Raff**, Menlo Park, CA (US); **David Yeh**, Redwood City, CA (US)

(73) Assignee: **Apple Inc.**, Cupertino, CA (US)

(**) Term: **14 Years**

(21) Appl. No.: **29/473,671**

(22) Filed: **Nov. 25, 2013**

CLAIM

The ornamental design for an electronic device, as shown and described.

DESCRIPTION

FIG. 1 is a top, front, left perspective view of an electronic device showing our new design;

FIG. 2 is a top view thereof;

FIG. 3 is a bottom view thereof;

FIG. 4 is right side view thereof;

FIG. 5 is a left side view thereof;

FIG. 6 is a front view thereof; and,

FIG. 7 is a rear view thereof.

The dashed broken lines are for the purpose of illustrating portions of the electronic device, and the dot-dash broken lines represent an unclaimed boundary; the broken lines form no part of the claimed design.
